UNITED STATES PATENT OFFICE.

ALBERT E. BEALL, OF CLINTON, IOWA, ASSIGNOR TO CORA E. BEALL, OF CLINTON, IOWA.

BED-BOTTOM.

SPECIFICATION forming part of Letters Patent No. 728,438, dated May 19, 1903.

Application filed January 2, 1902. Serial No. 88,190. (No model.)

To all whom it may concern:

Be it known that I, ALBERT E. BEALL, a citizen of the United States, residing at Clinton, in the county of Clinton and State of Iowa, have invented a new and useful Bed-Bottom, of which the following is a specification.

This invention relates to bed-bottoms.

The object of the invention is to provide a bed-bottom which in use shall be thoroughly effective in distributing the weight of the occupant, which shall be noiseless, and which while readily yieldable in use shall possess sufficient resisting power to prevent it from sagging to an objectionable degree.

15 A further object is to provide a bed-bottom in which the greatest resisting power shall be centered at the point where the greatest weight is disposed, thereby obviating an objection inherent in many woven-wire mat-tresses in which the center portion thereof will sag under weight to such an extent as to render it uncomfortable in use.

With these and other objects in view, as will appear as the nature of the invention is better understood, the same consists in the novel construction and combination of parts of a bed-bottom, as will be hereinafter fully described and claimed.

In the accompanying drawings, forming a part of this specification, and in which like numerals of reference indicate corresponding parts, there is illustrated one form of embodiment of the invention, together with a modification thereof capable of carrying the same into practical operation, it being understood that the elements therein exhibited may be varied or changed as to shape, proportion, and exact manner of assemblage without departing from the spirit thereof, and in these drawings—

Figure 1 is a view in plan of a bed-bottom constructed in accordance with the present invention. Fig. 2 is a view in transverse section. Fig. 3 is a view in longitudinal section.

45 Fig. 4 is a view in plan of a modified portion of the bottom.

Referring to the drawings, 1 designates the frame of the bed-bottom, comprising side bars 2 and end cleats 3, disposed on the upper edges of the side bars and secured thereto in any suitable manner.

The bed-bottom comprises a plurality of supporting-strands 4, each composed of two pieces of wire, one terminal of each of which is connected with a metallic batten 5, secured to each of the end cleats and projecting inward beyond the inner edge thereof. The manner of assembling the supporting-strands with the cleats consists in this instance in providing the latter with a plurality of orifices corresponding in number to that of the strands and in bending the terminals of the strands into hooks 6 to engage the orifices. This form of connection will be found thoroughly efficient and durable in use and may be readily and cheaply effected; but it is to be understood that the invention is not to be limited to this precise manner of assembling the said parts, as other means may be adopted for the purpose and still be within the scope of the invention.

As above stated, each strand is composed of two sections, which are adapted in use to yield longitudinally when weight is applied to the bottom, and to hold the two strand-sections in operative position for use two cross-strands 7 are employed, which constitute pressure-eveners. To associate the eveners with the supporting-strands, the terminals of the latter are bent into loops or eyes 8, and through these the eveners are passed and lie under the supporting-strands, the terminals of each of the eveners being held from disconnection with the eyes of the terminals of the two outside supporting-strands by providing the terminals of the eveners with eyes or loops 9, which constitute stops for the purpose defined, or, if preferred and as will be obvious, the eyes 9 may be interlooped with the eyes 8 of the supporting-strands for the same purpose. The pressure-eveners are, as shown in Fig. 1, constructed of corrugated wire, and are thereby adapted to yield to transverse pressure; but, if preferred, they may be made of straight wire, as shown in Fig. 4.

The terminals of the supporting-strands overlap each other any preferred distance, and inclosing the overlapped portions and bearing at their ends against the eveners is a series of coiled springs 10, one for each of the supporting-strands, these springs exerting resistance to yielding by having their

whorls compressed instead of being extended, as usual. This function is obtained by disposing the springs between the eveners, which latter, as will be readily understood by reference to Fig. 1, are drawn toward each other by the opposite movement of the members of the supporting-strands when pressure is applied to the bed-bottom, thereby contacting with the ends of the springs and compressing them. This movement is secured by connecting the terminals of the supporting-strands at the right-hand end of the bed-bottom with the evener at the left-hand end and the terminals of the supporting-strands at the left-hand end of the bottom with the evener at the right-hand end. By securing the desired yielding movement of the bed-bottom by compression of the springs all danger of breaking the latter will be entirely obviated, and, further, the desired yield of the springs will be secured with less longitudinal movement of the supporting-strands than if the said springs were stretched or extended, as with beds of this character generally in use.

When weight is applied to the bed-bottom, the pressure is equalized by the eveners across the whole width of the bottom, it being apparent that as the terminals of the eveners are positively associated with the supporting-strands they can have practically no transverse movement, so that on weight being applied to the bed-bottom, if near one side thereof, this weight will cause the eveners of that side to be drawn together, and this movement will be transmitted entirely across the bottom and cause a contraction or compression of all the pressure-resisting springs, thereby positively obviating the tendency of one portion of the bed-bottom to yield objectionably to the exclusion of the other portions.

A bed-bottom constructed as herein described will be exceedingly durable in use, will not be liable to get out of repair, and by reason of its simplicity of construction may be manufactured and sold at a low figure.

Having thus fully described my invention, what I claim as new, and desire to secure by Letters Patent, is—

1. A bed-bottom comprising a frame, a plurality of longitudinal two-part supporting-strands having their outer terminals secured to the frame and their inner terminals over-

lapped at an intermediate point of the bottom and provided with eyes, pressure-eveners passed through the said eyes, and pressure-resisting springs inclosing the overlapped terminals of the strands and bearing against the said eveners. 55

2. A bed-bottom comprising a frame, a plurality of longitudinal two-part supporting-strands having their outer terminals secured to the frame and their inner terminals overlapped and provided with eyes, corrugated pressure-eveners passed through the eyes, and associated against disconnection with the outside supporting-strands, and pressure-resisting springs inclosing the overlapped terminals of the strands and bearing against the said eveners. 60 65

3. A bed-bottom comprising a frame, a plurality of longitudinal two-part supporting-strands having their outer terminals secured to the frame and their inner terminals overlapped and provided with eyes, pressure-eveners passed through the said eyes and disposed beneath the supporting-strands and having their terminals provided with stops to hold them against disconnection from the outside supporting-strands, and pressure-resisting springs inclosing the overlapped terminals 70 75 of the strands and bearing against the said eveners. 80

4. A bed-bottom comprising a frame, battens carried by the end cleats thereof and provided with orifices, a plurality of two-part supporting-strands having their outer terminals provided with hooks to engage the orifices and their inner terminals overlapped at a point intermediate of the length of the bottom and provided with eyes, corrugated pressure-eveners passed through the said eyes and having their terminals provided with stops to prevent disconnection from the outside supporting-strands, and pressure-resisting springs inclosing the overlapped terminals 85 90 95 of the strands and bearing at their ends against the said eveners.

In testimony that I claim the foregoing as my own I have hereto affixed my signature in the presence of two witnesses.

ALBERT E. BEALL.
